CLAIM

The ornamental design for sauna as shown and described.

DESCRIPTION

1. Sauna

2. Sauna

3. Sauna

4. Sauna

1.1 : Perspective

1.2 : Perspective

1.3 : Perspective

1.4 : Perspective

1.5 : Perspective

2.1 : Perspective

2.2 : Perspective

2.3 : Perspective

2.4 : Perspective

2.5 : Perspective

3.1 : Perspective

4.1 : Perspective

The designs represent cuboid saunas having as characteristic features a wooden or wood-like interior in a modern-looking relatively sleek and even exterior with glass or glass-like front panel, thereby giving the impression of a sauna in a frame; broken lines and color shaded areas in the reproductions depict portions of the sauna that form no part of the claimed design; figures 1.1-1.5 and 3.1 are in grayscale, figures 2.1-2.5 and 4.1 are line drawings; in perspective, figures 1.1, 1.2, 2.1, 2.2, 3.1, 4.1 depict left views; figures 1.3, 1.4, 2.3, 2.4, 3.3, 3.4 front views and figures 1.5, 2.5 right views of the respective designs.

1 Claim, 12 Drawing Sheets
